UNITED STATES PATENT OFFICE.

LEOPOLD KATZENSTEIN, OF NEW YORK, N. Y.

METALLIC ROD-PACKING.

SPECIFICATION forming part of Letters Patent No. 267,750, dated November 21, 1882.

Application filed April 8, 1882. (No model.)

To all whom it may concern:

Be it known that I, LEOPOLD KATZENSTEIN, of New York, in the county and State of New York, have invented a new and Improved Metallic Rod-Packings, of which the following is a specification:

This invention relates to an improved metallic packing, which may be used for piston-rods and other similar purposes—as, for example, for packing the joints of steam or other pipes; and the special object of this present invention is to produce a packing which shall be readily and easily put in place, and which, on account of its elasticity, will adjust itself and yield when, for example, there is some displacement or movement of the pipe joints or of the rod. The packing is also to be of such construction that steam and water will assist in keeping it right.

The invention consists in making the packing-rings hollow, and, by preference, triangular in shape, and alternating around the rod or pipe, so that the base of one triangular ring and the apex of the next triangular ring will come next to the surface of the pipe or rod to be packed. The rings will thus fit closely one against another, any number of them desired being used.

The invention also consists in making each of these packing-rings of a hollow tube, around which is wound or spun metallic wire, the whole being covered with a fibrous coating of asbestos, or equivalent fibrous strands, wound or spun around the wire to prevent the metallic surfaces of the several rings from coming into contact, said construction making this packing flexible, and adaptable to the purposes for which it is intended to be used, all has herein-after more fully described.

The invention also consists in leaving said hollow rings open at the ends or other places for the admission of steam or water to their interior.

In the accompanying drawings, Figure 1 represents a longitudinal sectional view of a stuffing-box, showing my improved packing placed therein, and its form and the manner of arranging it in the box and around a piston-rod. Fig. 2 is a plan view of the packing shown in Fig. 1, cut away at one portion of its

surface. Fig. 3 is a perspective view of a piece of the packing, and shows the method of winding the metal and fibrous covering around the tubular core. Fig. 4 is a cross-section of the tubular core of a packing-ring.

55

Referring to the drawings, A represents a stuffing-box; B, the gland or follower thereof. C is a piston-rod or other rod or piece to be packed, and D E F G H are five (more or less) packing-rings fitted around the rod C within the stuffing-box. These packing-rings are constructed as follows: Take a tube, a, of brass or other suitable metal whose shape is preferably that shown in cross-section in Fig. 4. This tube is continuous and hollow from end to end, and may be flexible, so that its ends can be brought together, as shown in Fig. 2. The edges of the metal of which this tube a is composed overlap each other slightly, as shown in Fig. 4, thus permitting a slight expansion and contraction of the tube, according as there may be pressure upon it from either side. Around this tube a, as a core, I wind a metallic wire, b, using preferably a soft wire, the coils of the wire being laid closely together around the tube to its entire length from one end to the other, and then they may be wound back again, breaking the joints of the first winding, as shown at b², Fig. 3, and then again wound back, if desired, breaking the joints of the second winding, as shown at b³, Fig. 3. The coils of the wire are kept from slipping off from the tube a by a flange or flanges d, which may be bent up on the tube at either end thereof, and which may also serve to clamp and hold the ends of the wire upon the said tube. When the winding with the wire b has been completed I wind over said wire around the tube a the asbestos or fibrous covering e, in a series of close successive coils, covering the whole surface of the wire b on the tube a. Instead of asbestos as a covering, I can use hemp, cotton, or other suitable fibrous material, and the same may be applied in strips or in any suitable manner which will effectually cover and protect the tube a and metallic covering b. When the tube a is of triangular shape, as already stated, its form is transmitted to the successive windings, b and e, and the whole ring, when finished, is triangular in cross-section. 100

I now have a flexible hollow strip, which is of the form shown or of other analogous form, and which may be made of various lengths, according to the diameter of the ring desired.

5 When a series of these rings is slipped over the joints of steam-pipes, or over rods or stems into the box A—one on top of the other—so as to make a close fit, as shown in Fig. 1, a metallic packing is formed, which is readily applied, and which adjusts itself to varying conditions, on account of its great flexibility. As the ends *d* of the packing ring are not fastened rigidly together, but only brought close when the packing is used, the steam or water will

10 penetrate between the two ends and enter the hollow portion of the tube *a*, filling it and acting as a further packing, and assisting in the objects for which my packing is intended; but if the ends of the tube be fastened very closely together, steam or water can be admitted to the hollow of the tube through apertures specially provided for that purpose.

15 In use, the triangular rings alternate to present alternately their bases and their apex to the surface to be packed, as shown in Fig. 1.

20 I can also make these hollow packing-rings with tubular cores of any angular form desired, or with a round or oval tubular core, the shape of the tubular core and the packing not being

essential, though I have shown a triangular 30 form of core and packing, as one best adapted to the purposes for which it is used.

I claim—

1. A packing composed of inner metallic tube, *a*, metallic covering *b*, applied directly 35 to said tube, and outer fibrous covering, *e*, substantially as herein shown and described.
2. A packing composed of inner tube, *a*, having end flange or flanges, *d*, and of the metallic covering *b* and fibrous covering *e*, 40 substantially as herein shown and described.
3. The hollow packing-rings of substantially the construction described, arranged one above another around the surface to be packed.
4. The hollow packing-rings having fibrous 45 covering and opening or openings in the inner tube to admit steam or water, substantially as specified.
5. In a packing-ring, the inner tube, *a*, made with overlapping edges, substantially as and 50 for the purposes specified.

This specification of my invention signed this 7th day of April, 1882.

LEOPOLD KATZENSTEIN.
